UNITED STATES PATENT OFFICE.

NELSON P. ALDRICH, OF PLAINFIELD, ASSIGNOR OF THREE-FOURTHS TO
ALFRED B. PITKIN, OF HARTFORD, CONNECTICUT.

STEAM-TRAP.

SPECIFICATION forming part of Letters Patent No. 241,581, dated May 17, 1881.

Application filed February 21, 1881. (No model.)

To all whom it may concern:

Be it known that I, NELSON P. ALDRICH, of Plainfield, in the county of Windham and State of Connecticut, have invented a certain 5 new and useful Improvement in Steam-Traps, of which the following is a description, reference being had to the accompanying drawings, where—

Figure 1 is a view, in central vertical longitudinal section, of a steam-trap made in accordance with my improvement. Fig. 2 is a view of a part of the valve-stem in vertical section on the plane $\alpha\alpha$. Fig. 3 is a detail view, showing the pivot of the ball-arm in horizontal section on plane $x'x'$.

The letter a denotes the case which contains the valve and other parts.

b denotes the inlet-orifice through which water and steam enter case a .
20 c denotes the double-elbowed exit-pipe, (meaning by "double-elbowed pipe" a pipe which has a vertical part with a lateral part at the foot and another lateral part running in a different direction at the top.) The lower end of 25 pipe c is stopped by a screw-plug, d , and the upper lateral arm runs out through one side or end of the casing, and is exteriorly provided with a key-lug, e , fitting to a corresponding lug-seat in the side of the casing, whereby 30 the whole pipe is held from swinging or rotation.

In the upper side of the lower lateral arm of pipe c a valve-orifice, f , is made, fitted with the valve g , which rises to open and falls to close. The stem of this valve is borne by 35 and has vertical reciprocation in the lugs h , which project from the side of the vertical part of the pipe c . The upper end of the valve-stem is mortised, and in the mortise is pivotally 40 hung the pendulous arm i , swelled into two convex cheeks at the pivot-point, so that the arm at this point may come in close contact with the sides of the mortise, preventing all side play, and yet give little contact of frictional surfaces. The lower end of this arm is 45 pivotally attached to the float-arm j , the purpose of this pendulous arm being to make the movements of the float-arm and the valve-stem synchronous, (vertically,) allowing the 50 float-arm a rotary motion of which the valve-stem does not partake, and to attain this end with the minimum of resulting friction, the

pivoted end of the float-arm is pivotally attached to the top of the upper lateral arm of the exit-pipe, the pipe bearing at this point 55 two lugs for that purpose, and the sides of the float-arm at the pivot-point being swelled into two convex cheeks, which come in close contact with the bearing-lugs, and so prevent side play of the float-arm and yet give little contact 60 of frictional surfaces. The free end of the float-arm bears a ball-float, which rests in the water, and whenever the water rises high enough the ball, in rising with it, raises the valve, opening it, and water flows out until the 65 water and the float with it sink, so that the valve closes.

It will be observed that the exit-pipe with its vertical and lateral parts, and the bearing-lugs for the valve-stem and for the float-arm, 70 are so located and arranged with reference to each other that all can be cast (with proper casting) in one piece. The double-elbowed exit-pipe forms an element of the combination specified in the first of the following claims, and 75 also under the name "double-elbowed pipe," an element of the combination specified in the second of the following claims. The double-elbowed pipe is hereinbefore defined as a pipe which has a vertical part with a lateral part 80 at the foot and another lateral part running in a different direction at the top. The shape herein defined and specified is an essential feature of the invention specified in the first claim, in that it gives me a pipe with its entrance below 85 the water-line and its exit above the water-line.

I claim as my improvement—

1. The combination of the casing, the double-elbowed exit-pipe, the reciprocating valve, 90 and the float-arm, all constructed and arranged substantially as described, and for the purpose set forth.
2. The combination of the exit-pipe, the reciprocating valve-stem, the pendulous arm i , 95 and the float-arm, all substantially as described, and for the purpose set forth.

In witness that I claim the same as my invention I hereto set my hand this 8th day of February, A. D. 1881.

NELSON P. ALDRICH.
